UNITED STATES PATENT OFFICE.

ARTHUR TREVOR DAWSON AND GEORGE THOMAS BUCKHAM, OF LONDON, ENGLAND,
ASSIGNORS TO VICKERS SONS & MAXIM LIMITED, OF WESTMINSTER, ENGLAND.

AUTOMATIC GUN.

No. 920,832.

Specification of Letters Patent.

Patented May 4, 1909.

Application filed November 26, 1906. Serial No. 345,232.

To all whom it may concern:

Be it known that we, ARTHUR TREVOR DAWSON, lieutenant Royal Navy, director and superintendent of ordnance works, and 5 GEORGE THOMAS BUCKHAM, engineer, both subjects of the King of Great Britain, residing at 32 Victoria street, Westminster, in the county of London, England, have invented certain new and useful Improvements in 10 Automatic Guns, of which the following is a specification.

This invention relates to automatic guns and has for its chief object to enable such guns to be made of considerably less weight 15 than heretofore. For this purpose we make the water-jacket of thin steel tubing suitably strengthened by corrugating its surface, the said corrugations being advantageously arranged lengthwise of the jacket and extending to within a short distance of its ends. 20 The said corrugations also increase the area of the jacket's surface exposed to the atmosphere, so that said surface will be kept cooler than in the case of a plain water-jacket as 25 hitherto generally employed with automatic guns.

In order that our said invention may be clearly understood and readily carried into effect we will describe the same more fully 30 with reference to the accompanying drawings in which:—

Figure 1 is a side elevation of a Maxim gun with our improved corrugated water-jacket. Fig. 2 is a longitudinal section, and Fig. 3 a 35 cross-section on the line 1—1 of the said water-jacket.

A is the water-jacket of thin steel tubing, the body of which is reduced to a suitable thickness and afterward corrugated. The 40 ends a' a² are left thicker than the body so that internal screw threads can be formed thereon for connecting the jacket to the gun casing B, and the front block C to the jacket. The corrugations a are in the example shown 45 formed longitudinally with respect to the jacket. Obviously, however, the said corrugations could be otherwise formed and arranged without departing from our invention.

50 What we claim and desire to secure by Letters Patent of the United States is:—

1. A water jacket for an automatic or other machine gun, comprising a thin steel corrugated tube substantially as and for the purpose specified. 55

2. A water jacket for an automatic or other machine gun, comprising a thin steel corrugated tube, thickened at the ends for connection with the gun substantially as and for the purpose specified. 60

3. A water jacket for an automatic or other machine gun, comprising a thin steel tube longitudinally corrugated and thickened at the ends for connection with the gun substantially as and for the purpose specified. 65

4. A water jacket for an automatic or other machine gun, comprising a thin steel tube longitudinally corrugated and thickened at the ends which are internally screw-threaded for connection with the gun substantially as and for the purpose specified. 70

5. The combination with an automatic or other machine gun of a thin steel corrugated tube and means for connecting it with the gun substantially as and for the purpose specified. 75

6. A water jacket for an automatic or other machine gun comprising a thin steel tube provided with depressions on its outer face thereby forming a series of corrugations. 80

7. A water jacket for an automatic or other machine gun comprising a thin steel tube provided with depressions on its outer face thereby forming a series of corrugations, said tube thickened at its ends whereby 85 the same can be connected with the gun.

8. A water jacket for an automatic or other machine gun, comprising a thin steel tube provided with depressions on its outer face, thereby forming a series of corrugations 90 which project both inwardly and outwardly beyond the surface of the tube.

In testimony whereof we affix our signatures in presence of two witnesses.

ARTHUR TREVOR DAWSON.
GEORGE THOMAS BUCKHAM.
